(57) **CLAIM**

I claim the ornamental design for an art deco style frame, as shown and described.

DESCRIPTION

FIG. 1 is a front elevation view of my new design;

FIG. 2 is a back elevation view;

FIG. 3 is top plan view;

FIG. 4 is bottom plan view;

FIG. 5 is a right side elevation view; and,

FIG. 6 is a left side elevation view.

The broken lines illustrate portions of the art deco style frame that form no part of the claimed design.
